US00D773922S

(12) **United States Design Patent** (10) **Patent No.:** **US D773,922 S**
(45) **Date of Patent:** **** Dec. 13, 2016**

(54) **COUPLING MEMBER**

- (71) Applicant: **Anki, Inc.**, San Francisco, CA (US)
(72) Inventors: **Charles Fiebig**, El Cerrito, CA (US);
Hanns Tappeiner, San Francisco, CA (US)
(73) Assignee: **Anki, Inc.**, San Francisco, CA (US)
(**) Term: **14 Years**
(21) Appl. No.: **29/516,979**
(22) Filed: **Feb. 9, 2015**

Related U.S. Application Data

- (63) Continuation-in-part of application No. 14/615,817, filed on Feb. 6, 2015.

(57) **CLAIM**

The ornamental design for a coupling member, as shown and described.

DESCRIPTION

FIG. 1 is a perspective view of the design of the coupling member;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines shown in the drawings represent portions of the coupling member that form no part of the claimed design.

1 Claim, 3 Drawing Sheets
